UNITED STATES PATENT OFFICE.

HENRY DAVEY, OF LEEDS, COUNTY OF YORK, ENGLAND.

LOW-PRESSURE STEAM-MOTOR.

SPECIFICATION forming part of Letters Patent No. 310,387, dated January 6, 1885.

Application filed July 7, 1884. (No model.) Patented in England February 23, 1884, No. 3,833.

To all whom it may concern:

Be it known that I, HENRY DAVEY, a citizen of England, residing at Leeds, county of York, England, have invented a new or Improved Construction of Low-Pressure Steam-Motor, of which the following is a specification.

My invention relates to a cheap and simple construction of steam-motor applicable where small power is required. This motor being worked by steam at a pressure not exceeding that of the atmosphere, the boiler is of a simple character, requiring no loaded safety-valve, gages, or appliances for feeding against pressure, and safe from all risk of explosion. The exhaust-steam is condensed, it may be, by surface condensation; but when the greatest simplicity is required it is condensed by injection.

I will describe the engine, referring to the accompanying drawings.

Figure 1 is a vertical section through the boiler and cylinder. Fig. 2 is a vertical section through the condenser and air-pump, which are situated at one side of the boiler; and Fig. 3 is a front view showing the fireplace and cylinder in section.

A is the fire-box within the boiler B, which is an upright cast-iron vessel, projecting forward at the bottom to give space for the fire-box A and to carry the bearings for the crank-shaft C, on which at one side of the boiler is the fly-wheel D. The upper part of the boiler also projects forward, accommodating within it the cylinder E. The piston-rod extends down through the cylinder-bottom, and is linked by the connecting-rod F to the crank on the shaft C. From the fire-box A a flue-tube, G, extends up through the body of the boiler and its steam-space, and in order to increase the heating-power water-tubes H may be fixed across the flue.

K is the condenser, which is a vertical tube placed at the side of the boiler, to which it is fixed. At the top it receives the exhaust-steam from the cylinder by a branch, L, which may have a cock or valve, M, as shown, to regulate the speed of the engine by more or less throttling the exhaust. A pipe, N, from a cistern a little higher than the water-level in the boiler, supplies an injection branch, I,

opening into the condenser, and a feed branch, N, opening into a vertical tube, U, which communicates with the steam and water spaces of the boiler, as shown in the transverse section, 55 Fig. 4. The feed branch has an opening fitted with a conical plug, V, which is attached to a float, W. The water in the tube U maintains the same level as that in the boiler, but is quiescent, and the float W, by raising or 60 lowering the plug V, regulates the feed so as to maintain the water at its proper level.

P is a small air-pump worked by a crank-pin on the fly-wheel shaft. This pump draws air and water from the condenser and discharges the water into a well, from which there is a lateral outlet, Q. The pump-valves are preferably made, as shown, so that both can be lifted out when required. By a hole, p, water from the well enters the pump to keep 70 the plunger lubricated and sealed against suction of air. The slide S of the cylinder E is worked directly from an eccentric on the fly-wheel shaft. Above the cylinder is a light safety-valve, X, which is not intended to be 75 loaded, as the construction of the boiler and the jointing to it of the fire-box and flue are, for the sake of simplicity, done in such a way as not to be suited for high pressure. The cylinder E is preferably made of gun-metal, 80 so as not to require lubrication of its piston.

Having thus described the nature of my invention and the best means I know of carrying the same into practical effect, I claim—

1. In a low-pressure steam-motor, the combination, with an upright boiler, of a fire-box and flue placed within said boiler, and a cylinder arranged wholly within the steam-space of the latter, and a condenser connected with the exhaust by a branch having a throttle-valve, substantially as described.

2. In a low-pressure steam-motor, the combination, with the boiler and a cylinder wholly contained within the steam-space thereof, of a condenser connected with the exhaust of the cylinder, a pump worked by a pitman upon the main shaft and drawing water and air from the condenser, and a well having a lateral outlet which receives the water, an aperture being formed between the well and the plunger-chamber for the admission of water to the latter, substantially as described.

3. In a low-pressure steam-motor, the combination, with a boiler having a lower projection to receive the fire-box, and an upper projection adapted to receive the cylinder, of a condenser, K, a water-supply tube, U, a feed branch, N, entering the latter, a conical valve, V, closing the feed branch, a float, W, connected to said valve, an injection branch, I, communicating with the condenser, and a pump withdrawing the water and air from the latter, substantially as described.

In testimony whereof I have signed my name to this specification, in the presence of two subscribing witnesses, this 21st day of June, A. D. 1884.

HENRY DAVEY.
